Patented Aug. 29, 1916.

John P. Wade Inventor
By his Attorney
Howard F. Hinman.

UNITED STATES PATENT OFFICE.

JOHN P. WADE, OF NEW YORK, N. Y.

DESIGN FOR A DUSTER.

49,588.

Specification for Design.

Patented Aug. 29, 1916.

Application filed June 20, 1916. Serial No. 104,820. Term of patent 3½ years.

To all whom it may concern:

Be it known that I, JOHN P. WADE, a citizen of the United States, residing in the borough of Manhattan, in the county, city, and State of New York, have invented a new, original, and ornamental Design for a Duster, of which the following is a specification, reference being had to the accompanying drawing, forming part thereof.

The figure is a front view of a duster showing my new design.

I claim:

The ornamental design for a duster as shown.

JOHN P. WADE.
